US0D1003727S

(12) **United States Design Patent** (10) **Patent No.:** **US D1,003,727 S**
(45) **Date of Patent:** **** Nov. 7, 2023**

(54) **CONTAINER**

(71) Applicant: **SHENZHEN LIYI99.COM, LTD.**,
Shenzhen (CN)

(72) Inventor: **Xuzhong Wang**, Shenzhen (CN)

(73) Assignee: **ABORDER PRODUCTS, INC.**, Grand
Prairie, TX (US)

(**) Term: **15 Years**

(21) Appl. No.: **29/788,651**

(22) Filed: **Jul. 9, 2021**

(30) **Foreign Application Priority Data**

Jan. 15, 2021 (CN) 202130028780.1
Jan. 15, 2021 (CN) 202130028799.6

(51) **LOC (14) Cl.** **30-03**

(52) **U.S. Cl.**

USPC **D30/132**

(58) **Field of Classification Search**

USPC D9/569, 560, 556, 432, 761, 429, 430,
D9/449, 447, 423–424, 525; D3/203.1,

(57) **CLAIM**

The ornamental design for a container, as shown and described.

DESCRIPTION

FIG. 1 is a top perspective view of a container showing our new design;

FIG. 2 is a front view thereof;

FIG. 3 is a rear view thereof;

FIG. 4 is a left view thereof;

FIG. 5 is a right side view thereof;

FIG. 6 is a top view thereof; and,

FIG. 7 is a bottom view thereof.

The broken lines shown in the Figures represent portions of the container that form no part of the claimed design.

1 Claim, 7 Drawing Sheets
